UNITED STATES PATENT OFFICE

105,140

DESIGN FOR A FINGER RING

Theodore Roffwarg and Alfred Savastano,
New York, N. Y.

Application May 15, 1937, Serial No. 69,369

Term of patent 14 years

To all whom it may concern:

Be it known that Theodore Roffwarg and Alfred Savastano, each a citizen of the United States of America, residing in the city of New York, county of New York, and State of New York, have invented a new, original, and ornamental Design for a Finger Ring, of which the following is a specification, reference being had to the accompanying drawing, forming part thereof.

We claim:

The ornamental design for a finger ring substantially as shown and described.

THEODORE ROFFWARG.
ALFRED SAVASTANO.
